GEORGE A. YOUNG AND ROBERT B. REED, OF DETROIT, MICHIGAN, ASSIGNEES TO
YOUNG BROTHERS COMPANY, OF DETROIT, MICHIGAN, A CORPORATION OF
MICHIGAN.

GAS-OVEN.

1,287,561.

Specification of Letters Patent. Patented Dec. 10, 1918.

Application filed June 12, 1916. Serial No. 103,211.

To all whom it may concern:

Be it known that we, GEORGE A. YOUNG and ROBERT B. REED, citizens of the United States of America, residing at Detroit, in the county of Wayne and State of Michigan, have invented certain new and useful Improvements in Gas-Ovens, of which the following is a specification, reference being had therein to the accompanying drawings.

10 This invention relates to ovens for japping, enameling and heat treating purposes, and the primary object of our invention is to utilize heated air for heating the interior of an oven or inclosure, the apparatus being disposed at the sides of the oven whereby the central portion thereof will provide sufficient clearance for articles to be treated in the oven.

Another object of our invention is to provide a heating apparatus for air and furnish the same with baffles, dampers and a system of ventilation which insures a high degree of efficiency in maintaining a uniform heat in the oven.

25 A further object of our invention is to provide an air heating apparatus of the return flue type having the flues thereof compactly arranged and disposed to be readily removed and cleaned, and this is accomplished without disturbing other parts of the apparatus or oven.

A still further object of our invention is to provide an air heating apparatus wherein the parts are constructed with a view of 35 reducing the cost of manufacture and at the same time retain the features by which durability, simplicity of construction, and means of assembling are secured. With such ends in view, our invention resides in the novel construction, combination and arrangement of parts to be hereinafter specifically described and then claimed.

Reference will now be had to the drawings, wherein—

45 Figure 1 is a longitudinal sectional view of the oven partly broken away and showing an air heating apparatus partly broken away and partly in section;

50 Fig. 2 is a cross sectional view of the oven, taken on the line II—II of Fig. 1, showing the heating apparatus in front elevation and partly broken away and partly in section;

Fig. 3 is a horizontal sectional view of a portion of the oven showing a heating apparatus in plan;

Fig. 4 is an enlarged cross sectional view taken on the line IV—IV of Fig. 3;

Fig. 5 is an enlarged horizontal sectional view taken on the line V—V of Fig. 1;

Fig. 6 is a similar view taken on the line VI—VI of Fig. 1, and

Fig. 7 is a similar view taken on the line VII—VII of Fig. 1.

In describing our invention by aid of the views above referred to, we desire it to be understood that the same are merely illustrative of an oven as now in use, and we do not care to confine our invention to the precise construction and arrangement of parts shown. The following description is therefore to be broadly construed as including substitute constructions and arrangement of parts which are the obvious equivalents of those to be hereinafter referred to.

In the drawings, 1 denotes a box-like or rectangular structure constituting an oven or inclosure, and this oven has double walls or inner and outer shells with a suitable insulation material therebetween. The side walls of the oven are designated 2 and the front wall 3 of the oven has a doorway 4 adapted to be closed by a door 5, said door being constructed similar to the walls of the oven.

In the oven, at each side wall 2 thereof, is an air heating apparatus, and the space between these apparatus provides sufficient clearance for articles to be heat treated within the oven. As the apparatus are identical in construction we deem it only necessary to describe in detail one of the apparatus, particularly that at the left hand side of Fig. 2 which has been illustrated in the remaining figures of the drawing.

On the bottom of the oven is the burner 95 housing extending from the front wall 3 to a point in proximity to the rear wall 6 of the oven, said burner housing having the front end thereof open and the rear or inner end thereof closed. The burner housing comprises side walls 7 and 8 connected by horizontal partitions 9 and 10, said partitions co-operating with the side walls 7 and 8 in providing a secondary air intake flue 11 which is open to the atmosphere at the front wall 3 and has an extension 12 open at the rear wall 6. The partition 9 forming the top of the flue has longitudinally disposed openings 13, and straps 14 for an apertured damper 15 slideable below the partition 9 for 100 105 110

- regulating the amount of air passing through the partition 9. At the forward end of the damper 15 there is an apertured side extension 16 disposed above an apertured bracket 17 carried by the forward end of the burner housing. The extension and bracket apertures determine the positions of the damper aperture relative to the openings 13.
- 10 Mounted in the front and rear walls of the burner housing is a longitudinally disposed burner pipe 18 having the outer end thereof provided with an air mixing device 19 adapted for connection with a suitable 15 gas or fuel supply (not shown). Above the burner pipe 18 is a baffle plate 20 supported on frames 21 suitably disposed throughout the length of the burner housing.
- 10 The front end of the burner housing has 20 a hinged door 22 and this door has an opening 23 and an angularly disposed mirror or reflecting plate 24, whereby the burner flames within the housing may be readily observed from the exterior of the oven and 25 properly regulated.
- 10 The burner housing provides a combustion chamber 25 below and above the baffle plate 20 and contiguous to the front wall 3 of the oven the burner housing has a vertical connection 26 to a flue box 27, said flue box being disposed at the inner side of the heating apparatus with one of its walls in vertical alinement with the wall 8 of the burner housing. The flue box 27 is rectangular in 35 cross section, and extends in proximity to the roof of the oven.
- 10 At the inner or rear end of the burner housing there is a similarly offset intake flue box 28 and disposed in parallelism with 40 these intake flue boxes are exhaust flue boxes 29 and 30. The exhaust flue boxes 29 and 30 have the lower ends thereof resting on the top of the burner housing, as shown in Fig. 4 and the upper ends of said exhaust flue 45 boxes extend through the roof or top of the oven.
- 10 The intake flue boxes 27 and 28 are provided with spaced nipples 31 disposed in lateral planes and at an obtuse angle to the 50 walls of the boxes. The exhaust flue boxes 29 and 30 have similar nipples 32 with the nipples of the exhaust flue box 30 in alinement with the nipple of the intake flue box 27, and the nipples of the intake flue box 28 55 in alinement with the nipples of the exhaust flue box 29. The nipples of the intake flue box 27 are connected to the nipples of the exhaust flue box 30 by flues 33 and the nipples of the intake flue box 28 are connected 60 to the nipples of the exhaust flue box 29 by flues 34, said flues being in superposed planes with the flues 33 at a reverse angle to the flues 34. In other words, the flues 34 cross the flues 33 and this arrangement 65 permits of the flues 33 and 34 being easily

removed without disturbing the flue boxes. The flues 33 and 34 are fitted over the nipples of the exhaust flue boxes 29 and 30 and the opposite ends of said flues are connected to the nipples of the intake flue boxes 27 and 28 by slide sleeves 35, which can be shifted on to the flues when it is desired to disconnect the same. This arrangement of the flues permits of easy access being had to the same with a very compact arrangement and when a flue is removed, the open nipples may be plugged and the apparatus used until another flue is placed in position.

10 In the intake flue boxes 27 and 28 are deflector partitions 36 distributing heated air 80 to groups of flues leading from said boxes, and in the exhaust flue boxes 29 and 30 there are similar deflector partitions 37, said partitions extending into the upper ends of the exhaust flue boxes to provide individual 85 flues for the exhaust of air from certain groups of flues 33 and 34. In the upper ends of the exhaust flue boxes are dampers 38, one for each individual flue therein, and it is through the medium of these dampers 90 that the exhaust of heated air from the apparatus may be retarded and the apparatus regulated to maintain a uniform heat.

10 In closing the greater part of the exhaust flue boxes 29 and 30 within the oven, are 95 ventilating ducts 39 having the lower ends thereof extending out of the front and rear walls of the oven and provided with screens 40. The upper ends of the ventilating ducts 39 open into the upper portion of the oven, 100 as best shown in Fig. 6, and the air admitted to the oven for ventilating purposes is heated by the walls of the exhaust flue boxes 29 and 30. The ventilating ducts also serve as an insulation for the exhaust flue boxes, 105 particularly since the ventilating ducts are between the side walls 2 of the oven and the intake as well as the exhaust flue boxes.

10 The burner housing has the roof or top 40^a thereof, between the connections 26, inclined, 110 as best shown in Fig. 4, to support an incline deflector 41. This deflector prevents accumulation of matter upon the top of the burner housing, which is necessarily very hot during the operation of the air heating apparatus.

10 In operation, the air for combustion purposes or the secondary air intake of the heating apparatus is regulated by the slide damper 15 and the heated air and products 120 of combustion pass upwardly through the connections 26 of the burner housing into the flue boxes 27 and 28. The heated air entering these flue boxes is deflected into groups of flues 33 and 34 to pass therethrough into 125 the flue boxes 29 and 30. The heated air in these exhaust flue boxes is utilized to heat a secondary air intake through the ventilating ducts 39, and as the walls of the various flue boxes and flues represent a large area, the in- 130

terior of the oven structure can be easily and quickly heated to subject articles therein to a desired temperature for japanning, enameling or other heat treating purposes.

5 It is through the medium of the individual dampers 38 that the passage of air from lower, intermediate and upper groups of flues 33 and 34 can be easily regulated and consequently the temperature of the oven.

10 Considerable importance is attached to the disposal of the flues 33 and 34, as the same can be easily and quickly removed when it is desired to remove soot and thoroughly cleanse the interior as well as the exterior of 15 the flues. As each heating apparatus is in proximity to a side wall of the oven structure, it is practically impossible to remove the flues 33 and 34 other than from the inner side of each apparatus. As a matter of fact, 20 the greater part of each heating apparatus can be removed or disassembled to be cleaned, thus allowing the entire interior of the oven to be cleansed.

With some installations for heat treating 25 products, it is possible to dispense with the air intake flue 11 as a secondary air supply in which instance the burners receive air for combustion through the exterior mixing device, or an independent heating agent is led 30 into the flue boxes. It is also possible to dispense with the ventilating ducts when sufficient oxygen is otherwise supplied, and in extreme cases additional ventilating ducts 35 may be associated with the intake flue boxes as well as the exhaust flue boxes.

What we claim is:—

1. In an oven, an air heating apparatus at 40 each side wall thereof, each apparatus comprising a burner housing having an air intake flue open at the front and rear walls of said oven, a damper as a part of said flue to control the supply of air to said housing, a burner in said housing, intake flue boxes at the ends of said housing and in communication therewith, exhaust flue boxes at the ends of said housing and in parallelism with said intake flue boxes, ventilating ducts around said exhaust flue boxes in communication with said oven and open at the front and rear walls thereof, and crossed detachable flues above said burner housing connecting said intake flue boxes to said exhaust flue boxes and removable from one side of said apparatus only.

55 2. In an oven, an air heating apparatus at each side wall thereof, each apparatus comprising intake flue boxes, exhaust flue boxes, in parallelism therewith and open at the top of said oven, ventilating ducts around said 60 exhaust boxes in communication with said oven and open at the front and rear walls thereof, crossed detachable flues connecting

said intake flue boxes to said exhaust flue boxes and removable from one side of said apparatus only, and means communicating 65 with said intake flue boxes adapted to supply heated air thereto.

3. In an oven, an air heating apparatus in said oven, comprising intake flue boxes, exhaust flue boxes in parallelism therewith 70 and having the ends thereof open at the top of said oven, means adapted for regulating the exhaust from the open ends of said exhaust flue boxes, ventilating ducts around said exhaust flue boxes in communication 75 with said oven and having the ends thereof open at the front and rear walls of said oven, crossed flues connecting said intake flue boxes to said exhaust flue boxes, and means below said flues adapted for supplying 80 heated air to said intake flue boxes.

4. In an oven adapted to be heated by hot air, means for circulating hot air at the walls of the oven comprising, in combination with a suitable source of hot air, intake 85 and exhaust flue boxes, crossed detachable flues connecting said intake flue boxes to said exhaust flue boxes, and means within said flue boxes for deflecting air into certain defined groups of flues. 90

5. In an oven adapted to be heated by hot air, the combination with a suitable source of hot air, of intake flue boxes in communication with said source of hot air, exhaust flue boxes in communication with said intake flue boxes, dampers associated with said exhaust flue boxes, ventilating ducts around 95 said exhaust flue boxes, and means in said intake and exhaust flue boxes adapted for deflecting air therein. 100

6. In an oven, the combination with a suitable source of hot air, of means for circulating hot air at the walls of said oven, comprising intake flue boxes in said oven in communication with the source of hot air, 105 exhaust flue boxes in parallelism with said intake flue boxes, crossed detachable flues connecting said intake flue boxes to said exhaust flue boxes, dampers in connection with said exhaust flue boxes, ventilating ducts 110 adapted to be heated by said exhaust flue boxes and establishing communication between said oven and the atmosphere, and means in said intake and exhaust flue boxes adapted for deflecting air into certain defined groups of flues. 115

In testimony whereof we affix our signatures in presence of two witnesses.
